ELECTROLYTIC CELL

Douglas Joseph Kennedy and Walter Egbert Barker, Shawinigan Falls, Quebec, Canada, assignors to Shawinigan Chemicals Limited, Montreal, Quebec, Canada, a corporation of Canada

Application November 30, 1940, Serial No. 368,068
In Canada September 10, 1940

3 Claims. (Cl. 204—263)

This invention relates to an electrolytic cell.

Objects

It is a principal object of the invention to provide a device of this nature having an arrangement of electrodes and semi-permeable diaphragms allowing separate circulation into and out of the cell of both anolyte and catholyte, with a minimum of intermixing and with no exposure of the electrolytes to the atmosphere.

It is a further object of the invention to provide an electrolytic cell in which the current efficiency is extremely high for the type of electrolytic process for which the cell is designed.

With these and other objects in view, a preferred form of cell according to the invention is featured by a combination of headers, tubular coaxially disposed anodes, cathodes and semi-permeable diaphragms, and connections thereto. The arrangement is such that a catholyte solution may be made to flow out of contact with the atmosphere from a storage container into the cell between the cathodes and semi-permeable diaphragms, and then back to the storage container; at the same time the anolyte solution may be circulated from a second storage tank through hollow anodes and between their surfaces and the semi-permeable diaphragms back to the storage tank. In this manner, both catholyte and anolyte solutions may be continuously withdrawn from the cell for the utilization of the electrolysis products and for replenishing the raw materials of the electrolysis. The cell may be provided with an outer casing in which a cooling liquid may be circulated.

Having thus generally described the invention, reference will now be made to the accompanying drawings which illustrate a preferred form of cell according to the invention, and in which:

Figure 1 is an elevation of this cell with the casing partly removed to show the cathodes.

Figure 2 is a plan view of the cell shown in Figure 1.

Figure 3 is a vertical cross section taken along the line 3—3 of Figure 2.

Detailed description

More detailed reference will now be made to the drawings. The cell includes a circular catholyte inlet header 10 of rubber-covered steel, "Karbate," hard rubber, or some other material resistant to chlorides. The header 10 is provided with an inlet pipe 15 and also includes outwardly extending flanges 11, to which are connected by means of bolts 12, a lower impregnated graphite

5 cathode tube sheet 20. A number of impregnated graphite tubular cathodes 30, leading from the catholyte inlet header 10, are set in openings in the tube sheets 20 and extend upwardly therefrom to meet an upper impregnated graphite tube sheet 40. The cathodes are cemented within openings in the upper and lower tube sheets with electrically conductive cement.

A catholyte outlet header 50 has a lower flange 51 connected by bolts 52 to the tube sheet 40. The header 50 is provided with an outlet tube 55. The header 50 also includes an upper flange 53 upon which there is mounted an impregnated graphite anolyte header 60. Above the anolyte header is mounted an impregnated graphite anode tube sheet 70, the header 60 serving to insulate the tube sheets 40 and 70 from one another. Extending downwardly from the tube sheet 70 are hollow cylindrical graphite anodes 80 which are co-axially arranged within the cathodes 30, these anodes being secured at their upper ends to bushings 81 screwed into threaded openings in the tube sheet 70. Electrically conductive cement completes the joint between the anodes, bushings and tube sheet.

20 Mounted on the anode tube sheet 70 is an impregnated graphite gas dome 90 having a flange 91. Bolts 100 extend downward through the flange 91, and also the anolyte header 60, the tube sheet 70 and the flange 53 of the header 50, thus connecting all these parts together.

25 A number of semi-permeable tubular diaphragms 110 are mounted with their top ends sealed in openings in the anolyte header 60, and extending downwardly therefrom. Rubber stoppers 111 are set in depressions in the anolyte header 60, to engage the ends of the diaphragms 110. Each of these diaphragms extends downwardly co-axially between an anode and a cathode, and is closed at the bottom. A spacer 112 at the bottom of each diaphragm holds a respective anode co-axial with the diaphragm. On the top of the header 10 and separating the chamber which it forms from the lower ends of the diaphragms is a perforated plate 17 of porcelain or any porous non-conducting chloride resisting material. This plate serves to support the weight of the diaphragms.

30 The anolyte header 60 is provided with an impregnated graphite gas outlet pipe 61 leading to the gas dome. An anolyte inlet tube 62 extends through the gas dome. An impregnated gas outlet pipe 63 also leads from the gas dome to permit collection of the gas. The anolyte header is also provided with an outlet 65 for the anolyte.

The positive electrical connection is made with the anode tube sheet 70, which is an electrical conductor leading to the anodes. The negative connection is made with the cathode tube sheet 40, which is a conductor leading to the cathodes.

A cylindrical casing 120 extends between the tube sheets 20 and 40 forming a compartment in which a fluid for cooling the electrodes may be circulated.

Operation

The operation of the cell will be better understood by a description of its use in the production of chromous chloride and chlorine as intermediates in the manufacture of ethylene chlorhydrin. It must, however, be understood that the invention is in no way limited to this particular use.

In the process of producing ethylene chlorhydrin, an aqueous solution of chromic chloride (CrCl_3) is pumped from a storage tank into the catholyte inlet header 10. The catholyte is caused to flow from the header up between the surfaces of the cathodes, and the semi-permeable diaphragms 110, into the catholyte header 50, and then through the outlet 55 to the catholyte tank.

The anolyte, a solution of hydrochloric acid which may contain some chromic chloride, is made to flow into the anolyte inlet header by way of the inlet tube 62. The anolyte flows by gravity down through the hollow anodes 80 and then up between their outer surfaces and the semi-permeable diaphragms 110 into the anolyte outlet header 60 and thence from the anolyte outlet tube 65 to the anolyte storage tank.

An electrical current is passed through the cell from the connections to the tube sheets 40 and 70.

Due to the electrolytic action which takes place chloride ions are discharged at the anode and chlorine gas is evolved, while at the cathode hydrogen ions are discharged which are immediately consumed in the reduction of the chromic chloride to chromous chloride. Any hydrogen not consumed in the said reduction will be evolved as gaseous hydrogen and will leave the cell with the catholyte solution.

At the anode surfaces, chlorine gas is evolved and passes from the anolyte header, through the pipe 61, into the chlorine dome, whence it is collected from the outlet pipe 63.

The anolyte, during its passage through the cell, becomes somewhat depleted of hydrochloric acid, due to the evolution of chlorine gas. It is therefore, made to circulate continuously through an absorber (not shown in the figure) countercurrent to a stream of hydrogen chloride gas so that the hydrochloric acid content of the anolyte is continuously replenished.

The catholyte is passed, countercurrent to a stream of acetylene, through a reactor tower (not shown in the figure). By this means the acetylene is hydrogenated to ethylene and the chromous chloride oxidized to chromic chloride. The catholyte is also passed countercurrent to a stream of hydrogen chloride in an absorber. This is to replenish the chloride ions lost by the catholyte during its passage through the cell, when some chloride ions migrated through the diaphragms to the anodes. The ethylene and the chlorine are subsequently reacted to form ethylene chlorhydrin.

It should be observed that the continuous production of chlorine and chromous chloride can

be carried out economically only in an electrolytic cell possessing the structural features and arrangement of electrodes and diaphragms peculiar to the cell herein described. Essential conditions for this process fulfilled by our cell are:

(1) Passage of both the catholyte and the anolyte into and out of the cell. In this way not only is the chromous chloride available for the hydrogenation of acetylene at a point outside of the cell, but both catholyte and anolyte may be conveniently enriched with hydrogen chloride.

(2) A minimum of intermixing of catholyte and anolyte. Diaphragms of low permeability, such as those made from aluminum oxide, are required to prevent the anolyte which is highly oxidizing due to the presence of dissolved chlorine, from mixing with the catholyte. Such mixing would result in greatly decreased current efficiency.

(3) Exclusion of the atmosphere from the circulating electrolytes. The chromous chloride containing catholyte will absorb oxygen from the air and rapidly lose its reducing power. The anolyte is saturated with chlorine gas which would be lost on exposure to the atmosphere.

(4) Relatively high linear velocities of the catholyte over the surfaces of the cathodes resulting in high current efficiencies. This condition is brought about by the coaxial arrangement of our cylindrical electrodes and diaphragms with a minimum spacing between cathodes and diaphragms.

While the cell has been particularly described in connection with the production of chromous chloride and chlorine in the manufacture of ethylene chlorhydrin, the combination of its structural features may have other uses and it is not wished that the description of this particular process be taken in a limiting sense. Moreover, the description of the material from which the parts of the cell are made has been particularly for use in the above process and might vary in other uses, particularly if the electrolyte and the products of electrolysis are not corrosive.

The applicants have found that for the electrically conductive parts of the cell the following materials are suitable. The anodes are of graphite, the cathodes of "Karbate," this being the trade-mark name of an impregnated graphite composition, the diaphragms are of another trade-marked product, "Alfrax" which is an aluminum oxide composition. For this particular process the headers are of rubber-covered steel. The chlorine dome is of impregnated graphite as are the outlet pipes.

It will be understood that various modifications may be made in this invention without departing from the spirit thereof or the scope of the claims, and therefore the exact forms shown are to be taken as illustrative only and not in a limiting sense, it being desired that only such limitations shall be placed thereon as may be imposed by the state of the prior art or are set forth in the accompanying claims.

We claim:

1. An electrolytic cell suitable for the production of chlorine and chromous chloride of the type having a plurality of electrode couples, in which the electrodes are hollow and tubular, each anode extends within the cathode for a major portion of its length, a semi-permeable diaphragm separates each anode from its cathode, comprising in combination, a gas chamber common to said plurality of electrode couples having

openings from which the anodes extend downwardly beneath the gas chamber, an anolyte outlet chamber beneath the gas chamber from which semi-permeable diaphragms extend, a catholyte outlet chamber beneath the anolyte outlet chamber from which the cathodes extend downwardly to a catholyte inlet chamber, each anode and semi-permeable diaphragm forming therebetween an anolyte passage extending from the gas chamber to the anolyte outlet chamber, each cathode and its semi-permeable diaphragm forming therebetween a catholyte circulation passage separated from said anolyte circulation passage and extending from the catholyte inlet chamber to the catholyte outlet chamber, a gas exit in the gas chamber, an anolyte inlet in the gas chamber, a gas exit from the anolyte outlet chamber to the gas chamber, an inlet to the catholyte inlet chamber, an outlet from the catholyte outlet chamber and respective electrical connections to the anodes and cathodes.

2. An electrolytic cell suitable for the production of chlorine and chromous chloride, comprising in combination, a horizontally extending gas dome, an anode tube sheet beneath said gas dome and connected thereto, said anode tube sheet and gas dome forming therebetween an anolyte inlet chamber, an anolyte inlet in said gas dome, a gas outlet in said gas dome, an insulated anolyte outlet header beneath said tube sheet and connected thereto, said tube sheet and said outlet header forming therebetween an anolyte outlet chamber, a gas passage extending between said anolyte outlet chamber and said inlet chamber, a catholyte outlet header connected to said anolyte outlet header, a cathode tube sheet beneath said catholyte outlet header, said cathode tube sheet and said inlet header forming therebetween a catholyte outlet chamber, said catholyte outlet header insulating the anolyte outlet header from the cathode tube sheet, a catholyte outlet in said catholyte outlet header, a second cathode tube sheet vertically spaced considerably apart from said first cathode tube sheet, a catholyte inlet header beneath said cathode tube sheet and connected thereto to form a catholyte inlet chamber, a plurality of elongated tubular cathodes having respective ends set in said respective cathode tube sheets and each having an open end communicating with said catholyte inlet and outlet chambers respectively, a plurality of hollow tubular anodes set in said anode tube sheet and each having an open end communicating with said anolyte inlet chamber and extending downwardly within said cathodes, a plurality of semi-permeable diaphragms set in said anolyte outlet head-

ers, each diaphragm extending downwardly between an anode and a cathode, each diaphragm having an open end communicating with the anolyte outlet chamber and a closed end, each semi-permeable diaphragm and adjacent anode forming therebetween an enclosed elongated anolyte circulation passage extending from the anolyte inlet header to the anolyte outlet header and separating an anode from a cathode, each cathode and its semi-permeable diaphragm forming therebetween an enclosed catholyte circulation passage extending from the catholyte inlet chamber to the catholyte outlet chamber, the catholyte and anolyte circulation passages being arranged for the circulation of the anolyte and catholyte out of contact with each other and out of contact with the atmosphere, and respective electrical connections to said anodes and cathodes.

3. An electrolytic cell suitable for the production of chlorine and chromous chloride, comprising in combination; four enclosed juxtaposed chambers including a first top chamber, a second chamber immediately below the top chamber, a third chamber immediately below the second chamber, a fourth chamber vertically spaced from and below the third chamber; a plurality of hollow tubular cathodes extending between the third and fourth chambers, a plurality of hollow elongated anodes extending from the first chamber and passing through the second and third chambers but out of communication therewith, the interior of each anode communicating with the first chamber and being axially positioned in relation to a cathode and extending therewithin, a plurality of semi-permeable diaphragms each arranged to separate an anode from a cathode, each semi-permeable diaphragm having an open end communicating with the second chamber and forming with the adjacent enclosed anode an elongated anolyte passage leading from the first to the second chamber, each cathode having an open end communicating with the third and fourth chambers to form with the adjacent diaphragm an enclosed catholyte passage separated from said anolyte passage and extending between the third and fourth chambers, an anolyte inlet to the first chamber, an anolyte outlet from the second chamber, a catholyte outlet from the third chamber, a catholyte inlet to the fourth chamber, a gas outlet from the first chamber, a gas passage from the second chamber to the first chamber and respective electrical connections to the anodes and cathodes.

DOUGLAS JOSEPH KENNEDY.
